GRINDING AND POLISHING MACHINE

Charles Delafontaine, Arlington, and Frank W. Kotler, Watertown, Mass.

Application August 22, 1945, Serial No. 611,936

8 Claims. (Cl. 51—133)

1

This invention comprises an automatic machine for polishing diamonds or other precious stones. An important field of use for the machine is in shaping and polishing the girdle of a diamond, that is to say, the circumferential medial band lying between the two faceted portions of the stone. The machine of this invention may be utilized either to provide a smooth circumferential girdle or one having any desired number of facets fashioned therein.

In the cutting of diamonds maximum efficiency is secured when the diamond is held at a predetermined cutting grinding angle with respect to its grain. This angle is found in accordance with the present invention by turning the diamond progressively in such a path that the area being cut is presented progressively at all angles to the lapping wheel and thus is ensured the optimum cutting angle during a substantial portion of the cycle.

The primary object of the present invention is to provide a fully automatic machine, compact and reliable in its mechanical construction, and accurate and fully automatic in its operation for carrying out the process above outlined. To that end an important feature of the invention consists in a machine having a lapping wheel rotatable about a fixed axis in combination with a diamond holder rotatable about an axis at right angles to that of the lapping wheel, and also rotatable bodily about a fixed axis eccentric with respect to that of the wheel. In a machine of this construction the diamond is rotated about its own axis and is bodily moved in a circular path upon the face of the lapping wheel so that successive areas are presented at different grinding angles to the face of the wheel. When a continuous polished girdle surface is desired, the two rotary movements of the diamond holder take place continuously and at different speeds. When it is desired to provide the girdle surface with facets, the rotation of the diamond about its own axis is effective intermittently and each area is held in grinding position for the desired length of time.

An important feature of the machine of this invention comprises a distinct and self-contained unit spindle mechanism including concentric shafts, a head carried by one of the shafts, diamond holding members, and means operated by the other of the two concentric shafts for rotating the members about the longitudinal axis of the diamond held thereby. This complete unit may be removed from the machine conveniently and expeditiously for convenience in inspecting the

2

diamond in process, or for removing it, or for properly presenting an unpolished diamond. Further, this construction permits the unit to be removed with the diamond in process and locked up for the night or for any period when it is necessary or convenient to interrupt the current operation.

These and other features of the invention will be best understood and appreciated from the following description of a preferred embodiment thereof, selected for purposes of illustration and shown in the accompanying drawings, in which:

Fig. 1 is a view in perspective of the complete machine,

Fig. 2 is a view in elevation, partly in section, of the diamond holding head shown in operative relation to the lapping wheel,

Fig. 3 is a view in elevation illustrating a modified form of driving mechanism, and

Fig. 4 is a sectional view showing portions of the head on an enlarged scale.

In the illustrated embodiment of the invention the machine comprises a rectangular base 10 carrying at one end a standard 11 in which 25 is mounted the lapping or polishing wheel. The standard 11 has a double tongue and groove connection with the base 10 and is connected to an adjusting lever 12 by which it may be conveniently adjusted longitudinally of the base 10 to 30 any position determined by an eccentric stop 13. Clamping means operated by a handle 14 are provided for clamping the standard and holding it stationary in any adjusted position. The details of the adjusting and clamping mechanism 35 are not herein shown since they form no part of the present invention.

The standard 11 is forked to provide bearings for a horizontal shaft 15 carrying at its right hand end an abrasive lapping wheel 16. Fast to the shaft 15 is a driving pulley 17. At its outer end the shaft 15 is backed up by a spring 18 which bears at one end against a collar on the shaft and at its outer end against an adjustable arm 19 carried by a horizontal rod 20 projecting rearwardly from the standard 11. The shaft 15 with lapping wheel 16 is permitted a slight axial yielding movement against the spring 18 in order definitely to limit the pressure of the wheel against the work. The proper limit to this pressure may be determined by adjusting the arm 19 upon the rod 20.

To the right hand end of the base 10 is secured a stationary standard 22 in which is mounted the spindle unit and its driving mechanism. The standard 22 is also forked at its upper end and

provided with semi-circular bearings 23 which are completed by removable cap plates 24. The cap plates extend rearwardly and each is forked to receive a clamping screw having a knurled nut 25 by which the cap plate may be clamped rigidly upon the standard 22. At its outer end each cap plate is connected by a short link 26 to a rearwardly extending portion of the standard 22. Accordingly, when the nuts 25 are removed, the cap plates 24 may be swung upwardly and rearwardly upon the links 26 so that the stationary bearings 23 are fully exposed and the spindle unit may be conveniently removed or replaced therein and then clamped in operative position.

The spindle unit comprises a hollow shaft 27 rotating in a pair of bushings 21 that fit the bearings 23-24, carrying at its right hand end a pinion 28 and at its left hand end a head 29 having transversely extending branches or forks offset substantially with respect to the axis of the shaft.

The pinion 28 is arranged to mesh with an intermediate gear 31 journaled on a stud projecting from the rear portion of the standard 22. That gear in turn meshes with a similar gear 32 located immediately beneath it, and the gear 32 meshes with a driving pinion 33 fast on a horizontal shaft 34 which is journaled in the standard 22. The shaft 34 carries a driving pulley 35 by which it may be driven from any suitable source of power.

The shaft 34 carries also a large driving pinion 36 which meshes directly with a pinion 37 fast upon the outer end of a solid shaft 38 which is rotatably and concentrically disposed within the hollow shaft 21. By the gear mechanism above described it will be seen that the shafts 27 and 38 are driven in the same directions, with the shaft 38 travelling at a somewhat faster rate of revolution.

At its extreme left hand end the solid shaft 38 carries a worm 39, and this in turn meshes with a worm wheel 40 fast to a short shaft 41 journaled in the branches of the head 29. The shaft 41 is shown in horizontal position in Fig. 1 and in vertical position in Figs. 2 and 4. The shaft 41 is provided at its lower end, as shown in Figs. 2 and 4, with a pinion 42 for rotating the diamond holding members or cups. The lower branch 30 and the upper branch 43 of the head 29 are provided with aligned bearings which are parallel to the bearings of the shaft 41. In one of these bearings, i. e., that shown in Fig. 4 as in the lower branch, is journaled the stem 44 of a diamond holding cup or member 45. Formed integral with this is a pinion 46 which meshes with the pinion 42 on the shaft 41. In the lower end of the journal for the stem 44 is provided a removable plug or stud 47. An anti-friction support is provided for the stem 44 by securing a hardened ball 48 to the lower end of the stem 44 and a similar ball to the upper end of the stud 47. The stud 47 is removably retained in the bore of the bearing by a collar screw 49 which is threaded into the face of the lower branch 30 and overlaps the end of the stud 47.

In the upper branch 43 of the head is journaled the stem 50 of a diamond holding cup or member 51. The stem 50 is supported upon ball thrust bearings by a stud 52 and that in turn is adjustably retained in place by a knurled screw 53 threaded into the upper face of the branch 43 of the head 29 and overlapping the end of the stud. Both the cup members 45 and 51 are provided in their opposed ends with conical re-

cesses shaped to fit and hold the diamond being processed. These holding members are readily interchangeable for others of different shapes. They may be separated from engagement with the diamond by turning the screw 53 so that the stud 52 is released, and clamped in holding position by turning down the screw 53.

It will be noted that the opening between the branches 30 and 43 in the head 29 facing the lapping wheel 16 is unsymmetrical in its shape, that is to say, the branch 30 is offset substantially more than the branch 43. This arrangement provides ample space for the worm and worm wheel drive to the shaft 41 and the geared connection between the shaft 41 and the holding cup 45. It will be understood that it is necessary to drive only one of these cups, in this case the cup 45, and that the cooperating cup 51 will be rotated by its engagement with the interposed diamond.

Having placed a diamond properly between the cups 45 and 51 and moved the lapping wheel standard 11 toward the right to a position corresponding to the desired lapping pressure, the machine may be set in operation by driving the lapping wheel at a speed of 1600 R. P. M. and the driven shaft 34 at a rate of 16 R. P. M., for example. Under these conditions the head 29 may be rotated at approximately 18 R. P. M. and the holding cups at approximately 1 revolution in about 28 minutes. The result is that the diamond is rotated against the lapping wheel about its own longitudinal axis at the slower rate and is simultaneously moved bodily in a circular path in which the cutting or grinding angle of the area of contact is continually being changed. The result of these two movements is to produce a smooth polished girdle in the diamond.

It will be understood, of course, that the speeds above suggested are illustrative only and may be widely varied in accordance with the requirements of the work in hand. It will be noted that the effective rotation of the worm 39 is a differential. Both the shaft 27 and the shaft 38 rotate in the same direction and accordingly it is only the number of revolutions made by the shaft 38 in excess of the number of revolutions made by the hollow shaft 27 that are effective to drive the worm wheel 40. For example, pinions 36 and 37 may both have sixty-four teeth, and the intermediate gears 33 and 28 may have forty and forty-one teeth or vice versa. In that case the gear 28 and the shaft 27 will gain one tooth in each revolution over the gear 33 and the shaft 38.

55. In Fig. 3 is shown an alternative connection to the shaft 38 by the use of which the rotation of the diamond about its own axis is made intermittent instead of continuous, and the surface of the girdle is formed as flat facets instead of being smooth. When it is desired to operate the machine in this manner a pinion 37' which is loose on the shaft 38 is substituted for the pinion 37 of Fig. 1, the intermediate gears 31 and 32 remain in mesh and a forty tooth pinion is substituted for the forty-one tooth pinion so that there is no differential movement between the two shafts and no rotation of the diamond while a facet is being cut thereon. The gear 37' is provided with a series of equally spaced holes 60, for example four, and with these cooperates a locking pin 61 mounted in an arm fast to the end of the inner shaft 38. The locking pin 61 serves to hold the pinion 37' and the shaft 38 in fixed relation for an interval of the lapping operation sufficient to form a flat facet. Mean-

while, of course, the rotary movement of the head 29 is carried out as before described. When one facet has been completed, the locking pin 61 is withdrawn and the gear 31' indexed to the next hole. When the gear 31' is provided with four holes, one quarter turn of the gear will correspond to 9° rotation of the diamond, giving forty facets in complete circumference.

When the indexing head is used, gears of an equal number of teeth are employed between the hollow shaft 27 and the driven shaft 34, and between the solid shaft 38 and the driven shaft 34. The result is that both shafts turn at the same rate and there is no effective rotation of the worm 39. In this indexing operation the only effective rotation of the worm is caused by moving the arm 62 from one hole to another, and this may be carried out either by hand or mechanically.

Having thus disclosed our invention and described in detail a preferred embodiment thereof, we claim as new and desire to secure by Letters Patent:

1. A diamond polishing machine for forming a continuous circumferential girdle about a diamond, including in its structure a lapping wheel rotatable about a fixed axis and spring means for holding the wheel in operative position, in combination with a pair of telescopically arranged shafts rotatable about an axis parallel to but eccentric with respect to the axis of the lapping wheel, a diamond holder carried by the said shafts and rotatable about an axis at right angles to that of the lapping wheel and also rotatable about a fixed axis eccentric with respect to that of said wheel, and a single common means for driving the holder about both of said axes.

2. In a diamond polishing machine having a lapping wheel rotatable about a predetermined axis, a diamond holder comprising a pair of telescopic shafts rotatable about an axis parallel and eccentric with respect to the axis of said wheel, a head carried by and rotatable with one of said shafts, diamond clamping cups journaled in the head to rotate about an axis at right angles to that of the telescopic shafts, and a driving train between the other of said shafts and said cups.

3. In a polishing machine or the like having a lapping wheel rotatable about a predetermined axis, mechanism for presenting a diamond to the wheel comprising a pair of concentric shafts, means for supporting and driving the shafts in the same directions about a common axis eccentric with respect to that of the wheel, a forked head carried by the outer shaft, holding cups journaled in the outer end of the head to rotate about an axis at right angles to that of the said concentric shafts, and geared connections located between the forks of said head for rotating one of the holding cups from the inner of the said shafts.

4. In a polishing machine or the like, a self-contained removable unit comprising a pair of concentric shafts journaled one within the other, a driving pinion on each shaft, a forked head on the outer of said shafts, a rotary diamond holder journaled in said head and arranged to present a diamond for cutting in the space between its forks, and geared connections between said holder and the inner of said shafts.

5. In a polishing machine or the like, a self-contained unit comprising hollow and solid

shafts arranged concentrically, a head carried by the hollow shaft and rotatable therewith, a diamond holder journaled in said head to rotate about an axis at right angles to the common axis of the shafts, and worm gearing interposed between the solid shaft and said holder, whereby the latter may be driven at substantially reduced speed through the medium of said shaft as the head is rotated.

10 6. A diamond polishing machine comprising a lapping wheel rotatable about a horizontal axis, a diamond holder rotatable about an axis parallel to the flat face of said wheel, means for rotating said diamond holder including inner and outer telescopically arranged shafts for

15 supporting the holder in a position adjacent to the wheel and offset with respect to its axis, and means for driving said shafts and thereby bodily swinging the holder in a circular path in a plane located parallel to the face of the lapping wheel and located wholly at one side of the axis of said lapping wheel.

20 7. In a diamond polishing machine, a lapping wheel, a holder comprising a forked head, a pair of opposed cups journaled therein and also movable endwise toward and from each other, anti-friction bearings located within the forks and supporting both cups, means outside the forks for controlling the longitudinal position of the

25 30 cups, inner and outer telescopically arranged shafts carrying said holder, and a driving connection with the inner of said shafts for rotating one of the cups while the head is being rotated by the outer shaft.

35 8. In a diamond cutting or polishing machine having a lapping wheel rotatable about a fixed axis, a removable spindle unit comprising inner and outer telescopically related shafts, a head carried by the outer of said shafts and

40 40 having a pair of angular arms offset with respect to the common axis of the shafts, a worm-driven shaft journaled in said arms, a diamond holder rotatably mounted in said arms and driven by said worm-driven shaft, and a driving worm on the inner of said telescopically related shafts.
